UNITED STATES PATENT OFFICE

2,439,629

MULTIPLE THERMOCHEMICAL CUTTING ATTACHMENT

Stewart N. Libby, Chicago, Ill.

Application March 20, 1947, Serial No. 736,014

1 Claim. (Cl. 248—214)

1

This invention refers generally to thermochemical cutting apparatus, and more particularly to means for mounting a plurality of torches on the torch bar of thermochemical cutting apparatus, and includes means whereby a selected number of similar longitudinally aligned extension members are separably secured together and secured to the specially designed bracket on the torch bar, the torches being adjustably mounted in clamps provided on the ends of spacer members securable on said extension members.

A primary object of this invention is to enable the operator of a thermochemical cutting apparatus to handle large sections of work and to make several cuts simultaneously, thus increasing the capacity and versatility of the apparatus.

Another object of this invention is to provide torch holding means which may be extended indefinitely by adding a greater number of sections, hereinafter referred to as extension members, the capacity of the machine being limited only by the number of extension members and torches available.

Still another object of this invention is to provide for adjustability of the torches in a plurality of planes and angular disposition to the work.

Still another object of this invention is to provide an attachment which may be used with several types of thermochemical cutting apparatus.

And a last object to be specifically mentioned is to provide a device of this character which is relatively inexpensive and practicable to manufacture, extremely simple and convenient to install, adjust and use, and which will give generally efficient and durable service.

With these objects definitely in view, this invention resides in certain novel features of construction, combination and arrangement of parts and portions as will be described in detail hereinafter and particularly set forth in the appended claim, reference being had to the accompanying drawings which form a material part of this application, and in which:

Figure 1 is a top plan view of this invention operatively applied to an adjustable torch bar mechanism;

Figure 2 is a vertical sectional view of the bracket, extension members, secured to a torch bar, the figure being designed to illustrate the construction of the bracket and the means used to separably secure sections of the extension member to said bracket and to each other;

Figure 3 is a perspective view of the bracket

and a portion of one of the sections of said extension member;

Figure 4 is a vertical longitudinal section view taken through one of the spacer members which are secured at one end to the said extension member and are adapted with a sliding bearing and a pinion for the adjustable mounting thereon of torches having a vertically disposed rack, one of said torches being indicated in the figure in dash lines; and

Figure 5 is a cross-sectional view of a portion of the clamp, taken on the line 5—5 in Figure 2.

Similar characters of reference designate similar or identical parts and portions throughout the specification and throughout the several views of the drawings.

Referring now to the drawings in detail, it will be noted that the environment wherewith this invention is to be used includes a torch bar 10, extensibly mounted by means of toggle link members 12 and 14 and a cross link member 16, to a portion of the frame 18 of a thermocutting and welding machine. The torch bar 10 is represented in the drawings as comprised of a tube which is square in cross-section, as best illustrated in Figure 2, and of considerable length. This torch bar provides support for the subject matter of this invention, the V-shaped bracket 20 having lip flanges 22 adapted to fit over diagonally disposed corners of this bar. The bracket is provided with a pair of reinforcing ribs 24 disposed centrally and exteriorly thereof, and a boss 26 which is drilled and tapped to receive a screw-threaded thumb screw 28. The inside surface of the bracket 20 is undercut, as at 30, so that the bracket contacts the square-sectioned torch bar 10 at the corners only. A block 32, having one face notched to correspond with the shape of a corner portion of the torch bar 10 is provided with an elongated slot 34, which slot is disposed transversely of the block and of a size to loosely receive the retaining pin 36 inserted through this slot and terminally secured to the boss 26. This construction allows the bracket 20 to be longitudinally shifted along the square sectioned torch bar 10 and the clamping of the bracket thereto at any desired position.

The laterally extending member, generally indicated by the numeral 38, is comprised of a plurality of similar tubular members 40, each of which is closed at the ends 42 and 44 thereof, the end 42 being provided with a screw-threaded stud 46 which is integrally secured thereto, and the end 44 being centrally drilled and tapped to re-

ceive a similar screw-threaded stud, whereby a plurality of these sections 40 may be separably connected to constitute the extension member 38, it being understood that the bracket 20 is drilled and tapped, as at 48, to receive one of these threaded studs 46. It is preferred that the bracket 20 be provided with a boss 50, aligned with one of the ribs 24, to provide a proper seating member for the end of the innermost section 40 of the extension member.

Right-angularly disposed members, hereinafter referred to as spacer members 52, are provided with spring clamp ends 54 and fastening bolts 56, thereby adapting the spacer members 52 for adjustable clamping thereof to the extending member 38, that is, to any one of the sections 40. The other end of each of the spacer members 52 is provided with a slide bearing 60 which has a laterally extending attachment member 62 rigidly secured to the spacer member 52.

Each of the slide bearings 60 has a cylindrical bore portion adapted to receive a torch 64 of conventional design. On the outer side of each of the slide bearings 60 there is provided a transversely disposed bearing 66, in which is mounted the shaft portion of a thumb screw 68, an intermediate portion of said shaft being provided with a pinion 70, adapted to coact with the rack 72, normally provided on the body portion of torches of the type which will be used with this invention.

The operation of this invention will be clearly understood from the foregoing description of the mechanical details thereof, taken in connection with the above recitation of the objects sought to be achieved by this invention, but, in recapitulation, it may be expedient to note that, although the angular disposition of the extending member 38 is not alterable, this member may be shifted longitudinally of the torch rod 10, and the spacer members 52 may be shifted rotationally on the sections 40. Further adjustability of the device is

attained by adjustment of the torches 64 vertically in the slide bearing 60. It will therefore be seen that a plurality of torches may be conveniently mounted on this device and that the above objects have all been amply attained.

Though there has been shown a particular embodiment of this invention, this application is not limited to this particular embodiment, but it is desired to include in the scope of this invention the 10 construction, combination and arrangement of parts and portions substantially as set forth in the appended claim.

What is claimed as new and desired to be secured by Letters Patent:

15 Means for mounting a plurality of torches on the torch bar of thermochemical cutting apparatus comprising a bracket longitudinally adjustably mounted on said bar, a plurality of similar longitudinally aligned sections separably secured together and secured to said bracket, clamps longitudinally adjustably mounted on said members and having adjustable attachment means for torches, said bracket including a block configured to fit a portion of said torch bar and slidably mounted within a recess in said bracket, a pin inserted through a slot in said block and secured to said bracket, and a thumb screw threadedly mounted in said bracket and operatively contacting said block.
